UNITED STATES PATENT OFFICE

167,199

SKIRT

Mason W. Fuhr, Brentwood, and Gladys T. Salazar, Los Angeles, Calif., assignors to Joan Roberts of California, Los Angeles, Calif., a corporation of California

Application November 29, 1951, Serial No. 17,563

Term of patent 3½ years

(Cl. D3—26)

To all whom it may concern:

Be it known that we, Mason W. Fuhr and Gladys T. Salazar, depose and say that we are respectively a citizen of the United States residing at Brentwood, California, and a citizen of the United States residing at Los Angeles, California, have invented a new, original, and ornamental Design for a Skirt, of which the following is a specification, reference being had to the accompanying drawing, forming a part thereof.

The drawing is a view showing in elevation a skirt front carrying our new design. The back side of the skirt is of conventional appearance.

We claim:

The ornamental design for a skirt, substantially as shown and described.

MASON W. FUHR.
GLADYS T. SALAZAR.
